DESIGN FOR A SCARF

Joseph Abouchar, New York, N. Y.

Application December 26, 1935, Serial No. 60,281

Term of patent 3½ years

To all whom it may concern:

Be it known that I, Joseph Abouchar, a citizen of the United States of America, residing in the city of New York, county of New York, and State of New York, have invented a new, original, and ornamental Design for a Scarf, of which the following is a specification, reference being had to the accompanying drawing, forming part thereof.

I claim:

The ornamental design for a scarf substantially as shown and described.

JOSEPH ABOUCHAR.
